UNITED STATES PATENT OFFICE.

FRANK J. REED, OF OMAHA, NEBRASKA, ASSIGNOR OF ONE-HALF TO ALVIN H. SIERT, OF OMAHA, NEBRASKA.

INTERNAL-COMBUSTION ENGINE.

1,415,481.

Specification of Letters Patent. Patented May 9, 1922.

Application filed December 3, 1920. Serial No. 427,980.

To all whom it may concern:

Be it known that I, FRANK J. REED, a citizen of the United States, residing at Omaha, in the county of Douglas and State 5 of Nebraska, have invented certain new and useful Improvements in Internal-Combustion Engines, of which the following is a specification.

The present invention relates to an internal combustion engine.

An object of the invention is to provide an engine of this type with a pair of pistons which are each connected to the crank shaft and arranged to move in opposite directions 15 and which are adapted to operate under impact for utilizing the expansive force of consuming gases to further increase the driving action on the crank shaft.

Another object of the invention is to provide a novel type of crank shaft and novel connections between the same and the inner and outer pistons for effecting the diametrically opposite thrusts upon the crank shaft at opposite sides of the crank shaft axis 25 whereby to exert a torque upon the crank shaft in the same direction and at the same time.

A still further feature of the present invention is to provide a novel structure of cylinder and mounting therefor whereby the intake and exhaust may be effected in a practical and thorough manner and wherein proper ignition may take place in the interior chamber between the heads of the oppositely moving and concentrically arranged 35 pistons.

With the foregoing and other objects in view, the invention will be more fully described hereinafter, and will be more particularly pointed out in the claims appended hereto.

In the drawings, wherein like symbols refer to like or corresponding parts throughout the several views,

Fig. 1 is a transverse section taken through an internal combustion engine constructed according to the present invention and taken through one of the cylinders thereof, parts being shown in dotted lines and broken 50 away for the purpose of showing the novel features of the present invention, the section being taken on the line 1—1 in Fig. 2;

Fig. 2 is a fragmentary side elevation of an internal combustion engine embodying the

features of this invention, one end of the 55 same being shown in section.

Referring to the drawings, 10 designates a cylinder block forming the upper part of a crank case and which is provided at opposite sides with outstanding bracket arms 11 60 by means of which the engine may be attached to a vehicle frame or other suitable support. The section 10 forms the frame of the engine and is provided in its upper portion with transverse webs 12 suitably spaced 65 apart and provided intermediate their ends with depending arms 13 having bearings 14 in their lower ends into which is fitted a crank shaft 15, the crank shaft being held in the bearings 14 by caps 16 in the usual manner. A lower section 17 of the crank case is detachably secured to the upper section 10 by bolts 18 or the like, and is preferably provided in its lower end with a perforated strainer plate 19 spaced above the bottom 70 and detachably held therein by bolts 20.

The crank shaft 15 is provided with a plurality of cranks 21 and 22, two for each cylinder of the engine, and the cranks 21 and 22 being arranged in alternate relation and 80 in pairs and being joined together preferably by disc portions 23 of the crank shaft which serve as means for counterbalancing the shaft to reduce vibration.

The engine may be provided with any desired number of cylinders, and, as shown in Fig. 2, the cylinders are preferably cast in pairs and the cylinder blocks are secured by bolts 24 to the frame 10 with their axes intersecting the axis of the crank shaft 15. 90 The cylinders 25 are closed at their upper ends by a detachable head 26 held to the cylinder block by bolts 27, suitable packing being used in the ordinary manner, and the head 26 is provided with a water jacket or space 95 28 from which leads the usual radiator connection 29 for effecting circulation of the water throughout the jacket 28.

In each cylinder 25 is disposed a pair of pistons 30 and 31. The piston 30 is of a cylindrical form, open at its lower end toward the crank shaft 15 and which is closed at its upper end by a removable head or plug 32 which is preferably screw threaded into the top of the cylinder 30 and provided with 100 tool-engaging lugs 33 to facilitate manipulation of the head 32 when the main head 26 is removed from the cylinder block.

The lower or inner end of the cylindrical piston 30 has at one side a wall extension 34 and is provided across its lower end with a preferably integral transverse web 35 arranged in spaced relation to the extension 34 and forming therewith a support for a wrist pin 36, the wrist pin being held in place by a lock nut 37 and adapted to pivotally carry the upper end of a connecting rod 38. The connecting rod 38 extends downwardly and is preferably offset lengthwise of the crank shaft 15 to register with the crank portion 22 of the crank shaft and upon which the connecting rod 38 is mounted.

The inner piston 31 has a wrist pin 39 upon which is mounted a connecting rod 40 which extends downwardly through the outer cylindrical piston 30 and has a pivotal connection upon the crank portion 21 of the crank shaft. It is thus evident that the pistons 30 and 31 are connected to the crank shaft 15 at diametrically opposed points, or at 180° apart so that the pistons move toward and from each other during rotation of the crank shaft.

Each cylinder 25 is provided on one side with an integral intake channel 41 to which is attached a manifold 42 leading from a carburetor 43. The cylinder head 26 is preferably provided in one side and in registry with the chamber 41 with a recess or chambered portion 44 into which is threaded a valve cage 45 carrying an intake valve 46 controlled by a spring 47 to normally seat in the cage and close the passage 44. The valve head 26 also has in its under side a compression chamber or recessed portion 48 communicating with the passage 44 and also with a passage 49 formed in the cylinder 25 and extending downwardly along one wall thereof and opening through a port 50 in the wall of the cylinder 25 and at such height as to register with a corresponding port 51 formed in the side wall of the cylindrical or outer piston 30.

The cylinder 25 is also provided at one side, preferably diametrically opposite the port 50, with an exhaust port 52 leading to a valve chamber 53 in which is located an exhaust valve 54. The valve 54 has a stem 55 which passes down through the chamber 53 and into the upper end of the base 10 of the engine. The rod 51 rests upon a cam 56 mounted on a cam shaft 57 journaled in the base 10. The cam 56 is adapted to lift the rod 55, and a spring 58 normally seats the valve 54 when the stem is relieved of the pressure of the cam.

A removable plug 59 is placed in the upper side of the valve chamber 53 to admit gases to the chamber for the removal of the valve 54 and also for grinding the valve seat. The cylinder 30, which forms the outer piston, is provided in its wall with an exhaust port

60 adapted to register with the exhaust port 52 and to admit escape of consumed gases from the interior of the cylindrical piston 30 at such times as the piston 30 is raised and the inner piston 31 lowered.

The gases are ignited in the upper end of the cylindrical piston 30 by spark from a spark plug 61 which is threaded into one side of the cylinder 25 opposite an opening 62 in said side of the cylinder 25 adapted to communicate with a spark opening 63 formed in the cylindrical piston 30 when the piston is lowered to approximately its lowermost compressing position. A high tension lead 64 is carried to the spark plug 61 from a suitable distributor 65 having a distributor shaft 66 driven in any suitable manner, such as shown, by the chain 67.

The chain 67 is driven from the crank shaft 15 and suitable sprockets or the like 85 are provided as is common in internal combustion engine structure. The cam shaft 57 which regulates the opening and closing of the exhaust valves 54 is also driven by the crank shaft 15 through a chain 68 or the like, the shaft 57 being preferably driven at the same rate of speed as that of the crank shaft 15. As shown in Fig. 2 the crank shaft 15 may be provided with the ordinary fly wheel 69 forming one member of a clutch, and it is of course understood that the engine may have any number of cylinders otherwise suitably grouped together than as shown and dependent upon the type of engine.

In operation the downward travel of the outer piston 30 creates suction in the top of the cylinder 25 with the result that the intake valve 46 is moved to open position against tension of its spring 47 and the suction is then transmitted to the chamber 41 and manifold 42. A charge of combustible fuel is thus taken into the top of the cylinder 25 and in the compression chamber 48 of the head.

Raising of the cylindrical outer piston 30 compresses the charge just taken into the chamber 48 and its passage 49, the passage 49 being closed by the imperforate portion of the wall of piston 30 and the combustible fuel being steadily and further compressed until the piston 30 has reached its highest position when the ports 50 and 51 are brought together and the fuel under pressure is permitted to escape into the interior of the piston 30 at the upper end thereof. This escape of the fuel under compression into the piston 30 is permitted because the inner piston 31 is moved downwardly at a rate proportionately to the rise of the outer piston and consequently the inner piston clears the intake opening 51.

As soon as the charge has been delivered to the top of the piston 30, the crank shaft has advanced sufficiently for moving the pistons 30 and 31 toward each other with the result

that the entrapped fuel is compressed between the heads of the pistons until the outer piston 30 is moved down into a position to bring the spark opening 63 opposite 5 the spark opening 62 of the outer cylinder. At this time spark is produced at the spark plug 61 and the entrapped gases are ignited. Explosion of the gases effects impact upon the under side of the head of the outer piston 30 and upon the upper side of the inner piston 31, causing the pistons to move apart with one piston forcing downwardly on one side of the crank shaft 15, and with the other piston forcing upwardly on the opposite side of the crank shaft to thus produce a two-fold pressure operating in the same direction to exert a turning moment upon the crank shaft 15. The crank shaft is thus balanced in its action as the thrust is not 20 impacted upon one side of the axis of the crank shaft, and a thrust is practically equally disposed at opposite sides to prevent undue pounding on the bearings or vibration to any appreciable extent.

25 After an explosion the rise of the inner piston 31 tends to eject the products of combustion out of the piston 30 through the exhaust opening 60, which, upon completion of the downward stroke of the piston 31 is 30 in registry with the exhaust port 52 of the outer cylinder 25.

At this time also the cam 56 is in position for maintaining the valve rod 55 elevated for holding the exhaust valve open. During 35 the completion of the cycle the piston 31 is further moved up into the piston 30 to compress a new charge and the exhaust ports 60 and 52 are moved out of registry.

I do not wish to be restricted to the size, 40 form, and proportions of the various parts, and obviously changes could be made in the construction herein described without departing from the spirit of the invention, it being only necessary that such changes fall 45 within the scope of the appended claims.

What is claimed is:—

1. In an internal combustion engine, the combination of a two-part crank case, the upper part of said case having transverse 50 webs with depending supporting arms having bearings in their lower ends, a crank shaft supported in said bearings, cylinders mounted upon the crank case, a pair of pistons mounted in each cylinder, said crank

shaft having a pair of offset cranks in registry with each cylinder, and independent connecting rods between the pistons and the crank portions of the crank shaft whereby said crank portions are adapted to move said pistons toward and from each other 60 during turning of the crank shaft.

2. In an internal combustion engine, the combination of a cylinder provided with a charge intake at its upper end and a charge outlet near its lower end, said cylinder also having a longitudinal passage in one wall leading from the upper end of the cylinder and opening into the cylinder at a point near the lower end thereof, a cylindrical piston mounted in the cylinder and having an intake port near its lower end adapted to register with said longitudinal passage when the piston is raised for admitting a charge to the interior of the piston, said piston also having in a piston wall an exhaust port 70 adapted to register with said exhaust at the side of the cylinder, a second piston slidable in the first piston and adapted when lowered to uncover said intake and said exhaust ports, a crank shaft, and spaced connections 80 on the crank shaft between the same and said pistons.

3. In an internal combustion engine, a cylinder having a compression chamber in its upper end and a passage leading from 85 said chamber to a point toward the lower end of the cylinder for admitting a charge thereat, a pair of telescoping pistons fitting in the cylinder, a crank shaft, connections between the crank shaft and the pistons for 90 moving the same toward and from each other, said cylinder having an exhaust port opposite the inlet of said passage, the outer piston having opposed and slightly offset intake and outlet ports adapted to align 95 with said passage and said exhaust port of the cylinder, and the second piston being adapted for movement to consecutively uncover the exhaust and intake ports, whereby to control the feed and exhaust of fuel from 100 within the outer piston.

In testimony whereof, I have affixed my signature in presence of two witnesses.

FRANK J. REED.
